(57) **CLAIM**

The ornamental design for a mount for rooftop article installation, as shown and described.

DESCRIPTION

FIG. 1 is a front elevational view of a mount for rooftop article installation showing my new design, a rear elevational view being symmetrical therewith;

FIG. 2 is a top plan view thereof;

FIG. 3 is a bottom plan view thereof;

FIG. 4 is a right side elevational view thereof;

FIG. 5 is a left side elevational view thereof;

FIG. 6 is a perspective view 1 showing the front, top and

right side views thereof; and,

FIG. 7 is a perspective view 2 showing the rear, bottom, and

left side views thereof.

The broken lines represent portions of the mount for rooftop article installation and form no part of the claimed design. The article is a mount for installing a rooftop article such as a solar cell module or a solar water heater. The mount is fixed on the roof, and the rooftop article or a support member that supports the rooftop article is attached to the mount.
